UNITED STATES PATENT OFFICE

2,488,416

GLOVE

Gustave A. Kurz, Columbus, Ohio

Original application May 11, 1944, Serial No. 535,126. Divided and this application August 2, 1945, Serial No. 608,494

2 Claims. (Cl. 2—169)

1

This invention relates to gloves, either fabric or leather and is a division of my co-pending application Ser. No. 535,126 filed May 11, 1944 for Gloves, which application has been abandoned.

An object of this invention is to provide in a glove an improved fourchette which will permit standardization of the digits or fingers thereof.

Another object of this invention is to provide an improved fourchette which may be formed of elastic fabric so that the glove will snugly engage about each finger, the elasticity of the fourchette providing for the snug fitting of the fingers of the glove in any position of the fingers.

A further object of this invention is to simplify the construction of the glove so as to eliminate the necessity of providing different size fingers and assuring a snug fitting for a glove irrespective of which side of the glove is worn on the palm side.

With the foregoing objects in view, and others which may hereinafter more fully appear, the invention consists of the novel construction, combination and arrangement of parts, as will be more specifically described, and illustrated in the accompanying drawings wherein are shown embodiments of the invention, but it is to be understood that changes, variations, and modifications may be resorted to which fall within the scope of the invention, as claimed.

In the drawings:

Figure 1 is a detail side elevation of a glove constructed according to an embodiment of this invention.

Figure 2 is a plan view of the fourchette embodied with this invention.

Figure 3 is a fragmentary enlarged sectional view, partly in elevation, taken on the line 3—3 of Figure 1.

Referring to the drawings the numeral 10 designates generally a glove, which embodies a palm or body 11, with a wrist portion 12 at the inner end thereof. The wrist portion 12 may be formed integral with the palm 11, or may be formed as a separate piece which is stitched as at 13 to the rear of the palm 11.

The palm 11 also has formed integral therewith a back which is of the same configuration as the palm 11, as shown more clearly in my prior Patent 1,625,368 issued April 19, 1927. The palm 11 has extended therefrom finger cots 14 which include finger forming members 15 which are integral with the material forming the palm 11, and the back of the glove, and there is secured between the finger forming members 15 a fourchette, generally designated as 31.

2

The fourchette 31 is designed for use as with unreversible gloves, and is constructed of an elongated piece of fabric having integral fourchette portions 32, 33, 34 and 35. The fourchette portions 34 and 35 are of substantially triangular configuration, being formed integral with the adjacent ends of the intermediate fourchette portions 33 and 32 respectively.

The inner edge 36 of the fourchette portion 34 is adapted to be disposed at an obtuse angle to the adjacent edge 37 of the fourchette portion 33 by folding the material so as to form a triangle 38 on one side of the strip and then stitching the folded triangular portion 38 along the lines indicated by the numerals 39 and 40.

The fourchette portion 35, which is formed integral with the fourchette portion 32, has an inner edge 41 thereof disposed at an obtuse angle to the adjacent edge 42 of the fourchette portion 32 by folding the strip to form a triangular fold, as indicated at 43 and then stitching the folded portion along the lines indicated by the numerals 44 and 45.

Inner lines of stitching 46 and 47 may be stitched through the folded portions 38 and 43 respectively, so that the triangular folds 38 and 43 will lie firmly against the adjacent side of the strip. The meeting edges of the fourchette portions 33 and 34 are defined oppositely from the edges 36 and 37 by straight edges 48 and 49 which form an obtuse angle substantially sharper than the angle formed by the inner edges 36 and 37.

The junction between the fourchette portions 32 and 33 is defined by straight edges 50 and 51 which are at an obtuse angle to each other and are on a sharper angle than the opposite edges 52 and 53. The fourchette portion 32 has a straight edge 54 which is disposed at an obtuse angle with respect to the adjacent straight edge 55 of the fourchette portion 35, and the obtuse angle formed by the edges 54 and 55 is a sharper angle than the angle formed by the edges 41 and 42.

The fourchette 33 also includes a narrow connecting strip 56 which is adapted to engage over the tip of one finger and the fourchette 32 also includes a narrow strip 57 engageable over another finger tip. The outer end of the fourchette portion 35 includes a narrow tip member 58, and the outer end of the fourchette member 34 includes a narrow tip member 59.

The opposite edges of the fourchette hereinbefore described are adapted to be secured to the finger forming members 15 by stitching 60, as shown in Figure 3, the edges of the fourchette

being inwardly folded and secured to the inwardly folded edges of the finger forming members 15.

The fourchette 31 may be constructed of inherently elastic material so that when the front and back portions of the hand covering are secured to the fourchette the latter will provide a means whereby the back and front portions of the hand covering will readily conform to the configuration of the hand, and the fingers.

While gloves have heretofore been formed with fourchettes made of fabric, these fourchettes would not provide for the snug fitting of the finger cots on the fingers whereas by forming the fourchettes as hereinafter described the fourchettes may be narrower than has been the practice heretofore and due to the elasticity of the fourchette the cot will snugly or tightly engage about each finger irrespective of the position of the finger. While attempts have heretofore been made to form the fourchettes out of knitted fabric in order to provide for stretching of the fourchette the knitted fabric has not been entirely satisfactory due to the fact that it will not contract to the desired degree in order to provide for the snug fitting of the cot on the finger. However, with a fourchette formed of inherently elastic material, a conforming finger cot can be more readily provided which will retain its shape for a longer period of time and will, therefore, provide for the snug or tight fitting of the cot on the finger in any position of the latter.

I claim:

1. In a glove, a continuous fourchette comprising a pair of outer triangular members and an intermediate triangular member disposed in edge abutting relation, said outer members formed with a transverse fold extending divergently inwardly from the apex thereof whereby the outer edges of said outer members will be at an obtuse angle and the inner edges of said outer members will be at an obtuse angle greater than that of the outer edges, narrow connecting members con-

necting said outer members with said intermediate member and a narrow finger tip engaging strip extending from the outer end of each of said outer members.

- 5 2. In a glove, a continuous fourchette comprising a pair of outer members and an intermediate member, said members being substantially triangular and disposed in edge abutting relation, the juncture thereof being defined by straight edges 10 at an obtuse angle on the inner edge of said fourchette and an obtuse angle on the outer edge sharper than said inner angle, the ends of said inner member abutting the adjacent edges of said outer members, the adjacent outer edges of inner member and said outer members being disposed 15 at an obtuse angle, the inner adjacent edges of said inner member and said outer members being formed at an obtuse angle greater than the corresponding outer angle by folding the members at the juncture thereof in a triangle having the apex 20 at the apex of said outer angle, narrow connecting members connecting said outer members with said inner member, and a narrow finger tip engaging strip extending from the outer end of each of 25 said outer members.
